Specification of Letters Patent.

Patented Dec. 31, 1918.

Application filed June 1, 1915. Serial No. 31,475.

To all whom it may concern:

Be it known that I, MAGNUS H. JOHANSON, a citizen of Sweden, residing at Rochester, in the county of Monroe and State of New York, have invented certain new and useful Improvements in Checkwriters; and I do hereby declare the following to be a full, clear, and exact description of the same, such as will enable any person skilled in the art to which the invention appertains to make and use the same.

This invention relates to printing machines of the kind known as "check protectors" which are adapted for printing the value upon a check or other commercial instrument, for preventing the fraudulent alteration of the instrument to make it appear payable for a larger amount than was originally intended to be conveyed. More particularly the invention relates to machines of this class employing inked type characters for impressing the paper and impregnating it with the printing ink.

One essential feature of a machine of this type is the thorough inking of the paper at every impression in order to make erasure more difficult, and it is, therefore, one object of the invention to provide a machine constructed to secure a uniformly sufficient application of ink to the paper.

Machines of this kind are frequently subjected to use for extended periods of time without attention from the operator and without renewal of the supply of ink. Another object of the invention, therefore, is to provide a construction which automatically insures a continuous supply of ink sufficient for extended operation of the machine.

Other objects will appear as the description proceeds reference being had by numerals to the accompanying drawings forming a part of this specification in which:

Figure 1 is a top plan view of the outside of the machine.

Fig. 2 is an elevation of the same from the left side.

Fig. 3 is a similar view in section showing the interior parts of the machine.

Fig. 4 is a vertical section on the line 4-4 of Fig. 3.

Fig. 5 is a top plan view of the interior of the machine, the cover of the casing being removed.

Fig. 6 is a sectional view, similar to Fig. 5, from the right side of the machine.

Fig. 7 is a vertical section showing the parts of the inking apparatus in elevation.

Fig. 8 is a central sectional view of the fountain ink container and parts.

Fig. 9 is an end view of the latter from the left.

Fig. 10 is a similar view partly in section from the right side of the container.

The present invention has to do with machines for indelibly marking a check or other commercial instrument with a monetary value for preventing the fraudulent alteration, or "raising" of the instrument, and there is provided in a machine of this type a plurality of individual type forms which may be used selectively in combination with a platen for impressing upon the instrument an expression of any desired value. The printing surfaces of the type forms and platen are so constructed as to disrupt the fibers of the paper simultaneously with the impression of the type so that the ink applied by the latter is absorbed into the body of the paper, making it very difficult to alter the impression so applied.

It is important in machines of this kind that the type be provided with a uniform and plentiful supply of ink so that the paper will be thoroughly impregnated with the ink at every impression, as otherwise, the protection afforded by the use of the machine will be impaired.

Furthermore, machines of this kind are often used intermittently under such conditions that they receive very little care, and yet are required to be ready for instant service. There is needed therefore, an inking apparatus which will uniformly and continuously ink the type forms, without attention by the operator, over quite extended periods of use.

To these ends the present invention is embodied in a machine comprising a casing 100 having a base portion 21 and an upper portion 22 secured to the base portion by means of screws 23. (Figs. 1 and 2). These portions of the casing are held in spaced relation, affording a horizontal slot 24 for receiving the work to be impressed, the base portion having a plate serving as a bed or support for the work. The upper portion

21 of the casing supports a type carrier 25 (Figs. 3 and 4) which is in the form of a cylinder, rotatably carried by a shaft 26, the latter being journaled at its ends in the 5 side walls of the casing. The carrier or cylinder is provided on its periphery with a plurality of individual type forms 27 arranged in spaced relation and extending parallel with the axis of the cylinder. Fixed 10 upon the shaft 26 is a gear wheel 28 with which is adapted to mesh a gear wheel 29 fixed upon a stub shaft 30 journaled in and extending through one wall of the casing and carrying upon its outer end a hand 15 piece or knob 31. It will be noted that the gear 29 is larger than the gear 28, so that by a convenient, partial rotation of the knob 31 the carrier 25 may be rotated to bring any desired type form into printing position 20 at the lower side of the cylinder, just above the slot 24.

For indicating the positions of adjustment of the type carrier the latter is provided with a pulley 31^a (Fig. 3) around 25 which is wrapped a belt 32 which extends upwardly in crossed relation and around guide pulleys 33 supported at the front and back of the casing and adjacent the top thereof, upon an angle piece 34 attached at its ends 30 to the casing. Slidably mounted upon this angle piece is a small carriage comprising a frame 35 carrying small grooved rollers 36 and 37 adapted to embrace and roll along the lower and upper edges respectively, of 35 the angle piece 34. Frame 35 is provided with lugs 38 having notches at the upper ends thereof in which rests the belt 32 which is engaged between these lugs by the upper end of a tension adjusting screw 39 supported by a lug 40 on the frame. By turning the screw 39 the tension of the belt may be adjusted, and the frictional resistance is sufficient to securely attach the frame 35 to the belt. The frame is provided at its upper 45 edge with a pointer 41 adapted to be moved up and down an indicating dial 42 supported beneath a flange or swell 43 formed in the cover plate 44 of the casing (Figs. 4 and 6).

50 Referring to Fig. 3, the gear 29 carries a stop pin 45 adapted to contact with a fixed lug 46 projecting inwardly from the side wall of the casing, thus limiting the rotation of the knob 31 and therefore limiting the extent of movement of the pointer 41 so that it may not be moved off the ends of the scale and into contact with the casing.

55 The dial 42 carries a plurality of characters arranged thereon substantially in a column extending from back to front of the machine, each of these characters corresponding with one of the type forms on the type carrier. The cover plate 44 is inclined downwardly toward the front of the 60 machine so that the dial is clearly visible to

the operator, hence, by turning the knob 31 and observing the position of the pointer 41 with reference to the characters on the dial, any selected type form may be quickly and conveniently brought to the common printing point above the work supporting slot 24. 70

The impression of the type character at the printing point upon the work is effected by a vertically reciprocating platen 47 (Figs. 3 and 4), which is constructed to 75 move upwardly through an opening in the bed plate and press the work placed in the slot 24 against the type character above. This platen 47 is carried in a slot 48 in the forward end 49 of a bell-crank lever 50. 80 Screws 51 are provided for adjusting the position of the platen 47 in the slot 48. The surfaces of the type characters and platen are provided with a succession of fine ridges and depressions, and the platen is so positioned that its ridges coöperate with the depressions of the type characters and vice versa, for the purpose of disrupting or shredding the fibers of the paper during the printing operation. This construction 85 is similar to that shown in Patent No. 793249, of June 27, 1905, to L. M. Todd for printing apparatus, and as this feature forms no part of the present invention, a description thereof is deemed unnecessary. 90

95 The lever 50 is carried by a rock shaft 52 journaled at its ends in the side walls of the casing, and the opposite end 53 of this lever extends vertically into position to contact with a cam surface 54 carried by a main 100 operating shaft 55. The latter shaft is journaled at its ends in the casing and extends through the casing at the right side of the machine where it has fixed thereto a crank arm 56 carrying a handle 57. It will be 105 clear, upon reference to Figs. 3 and 6, that as the shaft 55 is rotated in the direction of the arrows by means of the handle 57, the high portion of the cam 54 will contact with the arm 53 of the platen lever during the latter part of the rotation of the shaft and rock the lever, raising the platen into printing contact with the type.

110 The shaft 55 may be provided with a ratchet wheel 58, (Figs. 3 and 5) and a co-operating pawl 59 carried by the casing and urged into contact with the ratchet by a spring 60. This means serves to prevent operation of the crank in the wrong direction of rotation and insures complete operation 115 of the machine in every instance, and the full impression of the work.

120 As the successive use of several type forms is required to produce a complete impression, means are provided for feeding the 125 work step by step over the printing bed comprising a pair of knurled wheels 61 (Figs. 3 and 4) projecting into the slot 24 through openings in the bed plate. These wheels are fixed upon a shaft 62 journaled at its for- 130

ward end in a lug 63 depending from the bed plate, and at its rear end in the rear wall of the base portion of the casing. The shaft 62 is actuated by a pawl and ratchet device, 5 shown most clearly in Figs. 3, 4 and 6, and comprising a ratchet wheel 64 fixed upon the shaft 62, and a pawl 65 held in contact with the ratchet wheel by a spring 66. The pawl is pivotally carried by a lug 67 on a plate 68 10 which is rotatably mounted on the shaft 62. The plate 68 has pivoted thereto a link 69 which in turn is pivoted to a horizontal arm 70 at the lower end of a vertically extending plate 71. The plate 71 is provided with 15 a slot 72 embracing the shaft 62 as a means for guiding the movement of the plate. As the latter is reciprocated vertically, it will be clear that the plate 68 will be given a rocking movement about the shaft 62, and the 20 latter will be given a partial intermittent rotation by means of the ratchet and coöperating pawl, so that the wheels 61 will be partially rotated to feed the work. A retaining pawl for the ratchet wheel 64 is provided in 25 the spring plate 72.

The plate 71 is pivotally attached at 73 to a cross arm 74 fixed to the rear end of an arm 75 of a lever 76 which is carried by a spindle 77 journaled at its ends in the casing. The lever 76 has a forwardly extending arm 78 carrying a projection 79 which is adapted upon the rocking of the lever 76 to come into contact with one of a plurality of stop shoulders formed in the periphery 30 of a disk 80 fixed to the end of the type carrier, (see Fig. 6). These stop shoulders, it will be observed, are located at varying radial distances from the center of the shaft 26. Each stop shoulder corresponds with 35 one of the type forms on the carrier, and its radial distance from the center of the shaft 26 corresponds inversely to the length of its respective type form. Thus, as a given type form is positioned at the common printing point the corresponding stop shoulder is placed in position to be struck by the projection 79 for limiting the amount of movement of the lever 76, and therefore of the amount of rotation of the shaft 62. 40 The lever 76 is actuated by an oscillating arm 81 (Fig. 6) through a spring 82 which is connected at one end to the arm 81 and at its other end to the cross arm 74. This arm 81 extends upwardly from a hub 45 journaled on the spindle 77, the hub carrying a lug 83 adapted to contact with a pin 84 in the arm 75 of the lever 76. Thus the arm 81 has a yielding connection through the spring 82 with the lever 76 in one direction, but relative motion between these parts in the other direction is limited by the contact of lug 83 with pin 84. The hub of the lever 81 carries a pin 85 to which is attached one end of a spring 86, 50 the other end of which is fixed to the cas-

ing at 87. This spring tends to hold the upper end of the arm 81 in contact with the outline of a cam 88 fixed upon the main operating shaft 55.

The operation of the feeding device will 70 now be apparent. As the shaft 55 is rotated from initial position, the high portion of cam 88 immediately moves the arm 81 forwardly, which, in turn, through the spring 82 rocks the lever 76 until its motion is limited by one of the stop shoulders, after which the arm 81 merely stretches the spring 82 and continues its forward motion idly under actuation of the cam 88. The plate 71 is thus raised and through the pawl 80 and ratchet device imparts a slight movement of rotation to the feeding wheels 61. As the high portion of the cam 88 moves out of contact with the arm 81, the latter is returned to initial position by the spring 85 86, and by means of its positive connection in this direction with the lever 76 raises the latter and moves the pawl 66 idly over the ratchet 64 to its starting position.

Means for holding the work in contact 90 with the feed wheels are provided in the pressure rolls 89 journaled on a lever 90 (see Fig. 6), pivoted on a spindle 91 carried by the casing. The rear end 92 of lever 90 has attached thereto a spring 93 which 95 urges the rolls 89 into contact with the feed wheels. The part 92 has pivoted thereto at 94 the lower end of a vertical rod 95 which projects upwardly through the cover of the casing and carries a finger piece 96. By depressing the rod 95 the pressure rolls 89 may be raised out of contact with the feed wheels to allow the insertion or removal of the work. Means will presently be described for retaining the pressure rolls in raised 100 position, and also for automatically releasing them for clamping the work upon commencement of the printing operation.

Means for accurately centering and locking the type carrier in printing position are 110 provided in a plate 97, (Fig. 3) journaled upon a spindle 98 supported by the casing, and carrying a forwardly extending arm 99 provided with a point 100 adapted to engage in notches 101 in the periphery of 115 a disk 102 fixed to the type carrier. The point 100 and the notches 101 are formed with beveled sides and as the arm 99 is moved toward the disk 102, these beveled surfaces coöperate to accurately center a type 120 form at the printing point, and when the point 100 fully enters the notches, the type wheel is securely locked in its adjusted position. The plate 97 and arm 99 are rocked by means of a lug 103 on the plate and a co- 125 operating cam 104 on the main operating shaft 55. At the commencement of the rotation of shaft 55, the high portion of cam 104 engages the lug 103 and centers and locks the type carrier, and this locking 130

means is only released upon return of the shaft 55 to its approximate initial position.

The means for retaining the pressure rolls 5 in raised position and for automatically releasing them comprises a lug 105 at the lower forward end of plate 97, (Fig. 3) and a coöperating recess 106 in the rod 95. The spring 93 is attached at its upper end to a 10 lug 107 of the plate 97, and thus holds the plate with its lug 105 pressing against the rod 95, and it will be observed that the lug 103 does not extend into contact with the low portion of its cam 104. As the rod 95 15 is depressed to raise the pressure rolls, the lug 105 springs into the recess 106, thus holding the pressure rolls in raised position. Upon rotation of the shaft 55, however, and actuation of the centering device, 20 the lug 105 releases the rod 95 and the pressure rolls are moved into contact with the work by means of the spring 93.

The ink apparatus comprises an inking element for the type forms, embodied in an 25 inking roller 108 rotatably journaled upon a spindle 109 carried at the end of an arm 110 projecting downwardly from a sleeve 111 (Figs. 3, 5 and 7) journaled on a spindle 112 carried by the casing. The sleeve 111 30 has an upwardly extending arm 113 to which is attached one end of a spring 114, the other end of which engages an eye 115 in the arm 53 of the platen lever. This 35 spring holds the inking roller 108 in rolling contact with the type forms of the carrier, and also holds the platen in its lower position.

The spindle 112 supports also a sleeve 116 40 which carries forwardly extending spaced arms 117 and 118. An ink transfer roll 119 has trunnions 120 journaled in these arms, and this roll is held in contact with the inking roll 108 by means of a spring 121 attached at one end to the spindle 109, and at 45 its other end to a projection on the arm 118. The arm 117 has an upwardly extending portion at its forward end in which is fixed a spindle 122 (Figs. 7 and 8) extending parallel with the transfer roll. This spindle 50 carries the fountain container for the ink, which will now be described.

The ink container comprises a sleeve 123 55 rotatably carried by the spindle 122 and having at its ends flanges 124 and 125, and these flanges carry a cylindrical wall 126. There is thus formed a closed, annular container 127 for the ink. The container is rotatably nested within a cylindrical sleeve 128 which at one end, 129, is spun over the 60 end of the container 127. The sleeve 128 is fixed at its other end to a flange 130 upon the inner end of a sleeve 131. The sleeve 131 is fixed therein a pin 132 adapted to enter an open slot 133 in the end of the 65 spindle 122 to prevent rotation of the sleeve

128 on the spindle 122. It will be seen that the container 127 and its surrounding sleeve 128, together with the sleeve 131, may be freely slid off and on the end of spindle 122, the pin 132 engaging in the open slot 133. A nut 134 is provided which may be screwed upon the end of the spindle 122 for holding the parts in position on the spindle.

Referring to Fig. 8, it will be seen that the flange 125 of container 127 is spaced 75 from the flange 130, providing an annular space 135 between these flanges. Flange 125 is provided with one or more openings 136, and flange 130 has an opening, closed by a threaded stopper 137. There is thus provided a non-leakable means for supplying 80 ink to the container after the latter has been slid off the spindle 122 and withdrawn from the casing, as explained above. The spindle 122 has a shoulder 138, and within the space 85 141 between this shoulder and the arm 117 is rotatably carried a ratchet wheel 142 having sockets 139 in which are adapted to engage the ends of pins 140 fixed in the flange 124 of the ink container and forming a driving 90 connection between the ratchet and container. The pins 140 have a loose fit within these sockets so that they may be readily engaged and disengaged therefrom when the ink container is removed and replaced on 95 the spindle for the purpose of filling the same.

The stationary sleeve 128 is provided with a number of spaced openings 143 arranged 100 in a line parallel with the axis of the sleeve along the line of contact between the sleeve and the transfer roll 119, it being observed that the roll and spindle 122 are so spaced that the roll contacts lightly with the sleeve 128. The cylindrical walls of the container 105 127 are also provided with openings 144 arranged spirally about the container and so spaced axially thereof as to register with the openings 143 during the relative rotation of the container and sleeve.

A device for rotating the ratchet 142 comprises an elongated pawl 145 (Figs. 6 and 7) pivotally connected to the arm 53 of the platen lever at 146. The arms 117 and 118 are each provided with an upwardly extending lug 147 in which is journaled a spindle 148 having at its inner end an eccentric pin 149 adapted to fit slidably within a slot 150 in the pawl 145. The spindle 148 at its other 115 end projects from the casing and is provided with a small finger piece by which it may be rotated.

When the spindle 148 is turned to place the eccentric pin 149 in lower position the pawl 145 is lowered into position so that its 125 pointed end engages the teeth of the ratchet 142 and imparts thereto, intermittently, a slight rotational movement whenever the platen lever arm 53 is rocked to make a 130 printing impression.

When it is desired to render the fountain container entirely inoperative, the spindle 148 may be turned to place the pin 149 in its upper position, which raises the pawl 5 clear of the ratchet 142.

The openings 144 are so spaced circumferentially of the container (Fig. 10), and the relative positions of the container, ratchet wheel 142 and pawl 145 are so adjusted that during each partial rotation of the container one of the openings 144 will move from a position indicated in Fig. 10 at 144^a across one of the openings 143 to a position indicated at 144^b, allowing a small 10 quantity of ink to flow from the container to the roll 119. The openings 144, however, never come to rest opposite the respective openings 143. Since the openings 144 are spirally arranged, the ink will be applied to 15 the roll 119 successively at points spaced axially as well as peripherally of the transfer roll. As the roll 119 is in contact with the cylinder 128, its periphery sweeps off in 20 rotation all the ink which is allowed to flow 25 through the openings 143, and will thus keep the latter cylinder clean.

The operation of the inking apparatus will now be understood from a brief description. At each operation of the platen 30 the pawl 145 will rotate the ratchet 142, and consequently the ink container, through a slight angle sufficient to sweep one of the openings 144 across one of the openings 143, thus permitting a small quantity of ink to 35 flow to the transfer roll. The transfer roll being in contact with the ink roll 108 is turned by the latter as the type carrier is rotated to adjust the type forms to printing position, and the transfer roll sweeping 40 across the openings 143 takes up the ink discharged and transfers it to the inking roll. If it is desired to render the ink supply inoperative, this may be done by adjusting the spindle 148.

45 The casing is provided with an opening, indicated at 156, (Figs. 4 and 5) opposite the ink container to allow access to the latter for withdrawing it from the casing for the purpose of refilling with ink.

50 To protect the work from being smeared by the inked characters on the type wheel there is attached to the casing, over the work slot, a guard plate 151 (Figs. 2 and 4) which extends beneath the type wheel 55 and has an elongated slot of a size sufficient to allow the paper to be raised by the platen against the type form at the printing point, but protecting the paper from contact with adjacent type forms.

60 For locating the work in printing position there is provided at either side of the slot a gage bar 152 adjustably supported and guided by a screw 153 which passes through a slot in the gage bar and is 65 screwed into the casing. By means of this

screw the gage bar may be released, adjusted, and then clamped in place, the bar being provided with a pointer 154 moving over the scale 155 for indicating its position.

The operation of the machine is suggested 70 by the foregoing description and will be understood from a brief explanation. The pressure rolls having been raised by means of the finger piece 96 the check is inserted in the work supporting slot, and the type wheel is 75 rotated by means of the knob 31 to bring the initial character into printing position, as for instance, the line of stars shown at the bottom of the dial. The crank 57 is then given a complete rotation, which releases the pressure rolls for holding the work against the feed wheels, centers and locks the type wheel in exact position, feeds the work forward into position to receive the impression, supplies a small quantity of ink to the 80 transfer roll, and finally raises the platen to impress the work and returns the latter to initial position. The type wheel is then adjusted to bring the next character into position and the above operation is repeated. 85 If for instance, the amount desired to be printed is \$256.12, the pointer 41 is located successively opposite the dial characters "2", "Hundred", "50", "6", "Dollars", "12" and "Cents". After each of these adjustments 90 the crank is rotated to print the corresponding character, and at each rotation of the crank the fountain inking device is actuated to supply a small quantity of ink to 95 spaced points on the transfer roll. The 100 subsequent rotational adjustment of the type cylinder rotates the transfer roll by means of the inking roll, so that the ink is supplied directly to the latter for application to the type form.

Having thus described my invention, what I claim as new and desire to secure by Letters Patent is:—

1. The combination with a hand stamp comprising a type carrier settable to bring various type forms, selectively, to printing position, and a platen having a movement toward and from said carrier to effect an impression of the selected type form; of an automatic fountain inking mechanism 110 comprising an inking roll arranged to be brought into inking contact with the type forms by the setting movement of the carrier; an ink container, means for supplying ink from said container to said inking roll, 115 and means whereby movement of the platen to take an impression will operate the ink supplying means to supply ink to the inking roll.

2. The combination with a hand stamp 125 comprising a type carrier settable to bring various type forms, selectively, to printing position, a platen for co-operation with said type forms, and operating means including a pivoted lever for moving the platen 130

- 6 toward and from the type forms; of an automatic fountain inking mechanism comprising an inking roll arranged to be brought into inking contact with the type forms by the setting movement of the carrier, an ink container, and means connected with said pivoted lever and actuated by movement of the lever for supplying ink from the container to the inking roll.
- 10 3. The combination with a hand stamp comprising a type carrier settable to bring various type forms, selectively, to printing position, a platen for coöperation with said type forms, and operating means including 15 a movable lever for carrying the platen toward and from the type forms; of an automatic fountain inking mechanism comprising an inking element arranged to be brought into inking contact with the type forms by the setting movement of the carrier, an ink container, and a pawl and ratchet connection between the platen lever and ink container for supplying ink to said inking element upon movement of the lever.
- 20 4. In combination, a type carrier settable to bring various type forms, selectively, to printing position, a platen for coöperation with said type forms, said carrier and platen having a relative impressing movement, an inking element for supplying ink to the type forms during said setting movement of the carrier, a fountain ink container, and means actuated by said relative impressing movement of the carrier and 25 platen for supplying ink from the container to the inking element.
5. In combination, a type carrier settable to bring various type forms, selectively, to printing position, a platen for coöperation with said type forms, said carrier and platen having a relative impressing movement, an inking element for supplying ink to the type forms during said setting movement of the carrier, a fountain ink container including a valve, and means actuated by 30 said relative impressing movement of the carrier and platen for operating said valve and supplying ink from said container to said inking element.
- 40 6. The combination with a hand stamp comprising a type carrier settable to bring various type forms, selectively, to printing position, a platen, and operating means for effecting a relative printing movement of carrier and platen; of an inking roll arranged to be brought into inking contact with the type forms by the setting movement of the carrier, an ink container comprising 45 contacting surfaces having a movement relative to each other and provided with perforations arranged to register in passing during the movement of said surfaces to permit a flow of ink from said container to said inking roll, and means actuated by move- 50 ment of said operating means for effecting the movement of said container surfaces.
7. The combination with a hand stamp comprising a type carrier settable to bring various type forms, selectively, to printing position, a platen, and operating means for effecting a relative printing movement of said carrier and platen; of an inking roll arranged to be brought into inking contact with the type forms by the setting movement of the carrier, an ink container comprising a fixed sleeve having an opening at the lower side thereof, a cylindrical member rotatably nested within the sleeve and having an opening therein adapted to register in passing with the opening in said sleeve 55 to permit a flow of ink from the container to the inking roll, and means actuated by the movement of said operating means for effecting a step by step rotation of said member.
8. In a machine of the class described, the combination with a type carrier adjustable to set different type forms thereon at printing position, an ink applying roller in contact with the type on the type carrier, a fountain ink container comprising a stationary member and a movable member in close engagement one with the other, one of said members having perforations arranged *en échelon* and the other having perforations arranged in a row at an angle to the perforations in the other member, means for imparting a step by step movement to the movable member whereby to carry the perforations in it successively past the perforations in the other to permit passage of ink and means for transferring the ink to the ink applying roller.
9. In a machine of the class described, the combination with a type carrier adjustable to set any desired type thereon at printing position, an ink applying roller in contact with the type on the carrier, an automatic fountain inking mechanism comprising a stationary cylindrical shell and a rotary cylindrical shell in close contact therewith, one of said shells having a series of perforations spirally arranged around its circumference and the other a row of perforations parallel to its axis, means for imparting a step by step movement to the rotary shell whereby to cause its perforations to successively pass by the perforations in the other to permit ink to escape and means for transmitting the escaped ink to the ink applying roller.
10. In a machine of the class described, the combination with a type carrier adjustable to set different type forms thereon at printing position, an ink applying roller in contact with the type on the type carrier, a fountain ink container comprising a stationary member and a movable member in

close engagement one with the other, one of said members having perforations arranged *en échelon* and the other having perforations arranged in a row at an angle to the 5 perforations in the other member, and means for imparting a step by step movement to the movable member whereby to carry the perforations in it successively past the perforations in the other to permit passage of 10 ink.

11. In a machine of the class described, the combination with a type carrier adjustable to set any desired type thereon at printing position, an ink applying roller in

contact with the type on the carrier, an automatic fountain inking mechanism comprising stationary cylindrical shell and a rotary cylindrical shell in close contact therewith, one of said shells having a series of perforations spirally arranged around its circumference and the other a row of perforations parallel to its axis, and means for imparting a step by step movement to the rotary shell whereby to cause its perforations to successively pass by the perforations in the 20 other to permit ink to escape. 25
